UNITED STATES PATENT OFFICE.

ADÉLARD F. MARTEL, OF MONTREAL, QUEBEC, CANADA, ASSIGNOR OF ONE-FOURTH TO CHARLES AUGUSTE MARTEL, OF SAME PLACE.

MAIL-BAG.

SPECIFICATION forming part of Letters Patent No. 245,646, dated August 16, 1881.

Application filed December 24, 1880. (Model.)

To all whom it may concern:

Be it known that I, ADÉLARD F. MARTEL, of Montreal, Province of Quebec, Canada, have invented certain Improvements in Mail-Bags, 5 of which the following is a specification.

My invention relates to mail-bags; and it consists in providing the same with a jointed mouth-frame consisting of two parallel end or side sections and a series of intermediate sections jointed together and arranged to fold inward between the end or side sections, said joints being furnished with stops, whereby they are prevented from coming into line with each other, and are consequently caused to fold 15 readily inward.

The invention further consists in a tongue applied to one of the folding sections and arranged to close the passage through which a seal is applied to the lock, the lock-case being 20 specially adapted to receive said tongue.

In the accompanying drawings, Figure 1 represents a perspective view of my improved mouth-frame expanded; Fig. 2, a perspective view of the same folded; Fig. 3, an interior 25 view of the lock.

The object of my invention is to provide a mail-bag which may be properly closed and fastened without the delay and bother incident to those commonly in use, and one in which 30 the threading of bands, chains, or other fastenings through eyes or staples may be avoided.

To this end I provide a mouth-frame consisting of two parallel end sections connected by shorter intermediate sections jointed to the 35 end sections and to each other, and adapted to fold alternately in opposite directions, the shorter sections forming the two sides of the mouth-frame. By referring to Fig. 1 this construction will be readily understood.

A represents the frame as a whole, consisting of end sections, *a b*, and jointed side sections, *c c*. The sides are composed of short sections, preferably a little less than one-half the length of the end sections, and are hinged 40 or jointed to fold alternately inward and outward, the hinges being placed alternately on the outer and inner faces of the sections for this purpose, as shown. Thus constructed, the frame may be folded into a compact shape,

bringing all the short sections constituting the 50 sides face to face with each other and between and within the end sections, as shown in Fig. 2.

B represents a staple, firmly secured to the inner face of the end section *b*, and projecting therefrom toward the opposite end section. 55 This staple is of such length that when the frame is folded, as in Fig. 2, it shall extend into the case of a lock, *C*, applied either to the outer or inner face of the end section, *a*, the staple passing between the two folded sides, 60 which, being composed of sections a little less than half the length of the ends, do not meet when folded, and consequently leave a sufficient space between them to receive the staple.

In order the more perfectly to close the space 65 between the ends of the folded sections they may be notched or recessed slightly to receive the edges of the staple *B*, as indicated in Fig. 2; or the staple may be turned edgewise or with its flat faces in a vertical plane, in which 70 case, being of slight thickness, but little space would be required for it.

In order that the sides may fold readily, each section in the proper direction, the joints or hinges *d* are arranged to stand out of line 75 with each other when the frame is distended, as shown in Fig. 1, this result being conveniently attained by forming said joints or hinges each with a shoulder or stop, *e*, by which the sections are prevented from opening out fully 80 and forming a straight line.

In the drawings, the hinges are shown as applied separately to the joints, and in some cases it may be desirable in practice to follow this construction. Ordinarily, however, the 85 sections will be made from sheet or plate metal, and the joints or hinges will be formed directly thereon, in which case stops will be formed to prevent them from opening out straight. When constructed as shown in the drawings, the 90 ends of the sections will be beveled and caused to form stops, as shown.

The locking device may be of any desired mechanical construction; but the case *C* will be formed with a passage, *f*, through which a seal 95 may be inserted to cover the key-hole, as is well understood. For the purpose of closing this passage or opening and preventing the re-

moval of the seal, one of the sections of the frame, preferably the one adjoining the end section to which the lock is applied, is provided with a tongue, D, which enters the lock-case 5 and extends across the passage f, as shown in Fig. 3.

It is obvious that the ends instead of the sides may be jointed and adapted to fold, in which case a single joint at the middle, together with joints or flexible connections with the sides, would be sufficient.

The bag material may be applied in any convenient manner; but if made to encircle or envelop the frame, the joints of the latter should 15 afford sufficient space between the faces of the sections to accommodate the material.

The frame thus constructed is simple, cheap, and strong, and may be closed in an instant. When distended or opened it affords a large 20 opening of convenient shape to receive the matter to be placed in the bag.

Other fastenings may be employed, if desired, either in lieu of or in addition to that described.

I am aware that jointed sections have heretofore been arranged to fold inward between parallel ends or sides, and I do not broadly claim such construction.

Having thus described my invention, what I claim is—

1. A mouth-frame for mail-bags, consisting of two parallel end or side sections connected by intermediate jointed sections adapted to fold inward between them, the joints being furnished with stops, whereby they are prevented 35 from coming into line with each other, substantially as and for the purpose set forth.

2. In combination with a folding mouth-frame, a lock provided with a seal-passage, and a tongue secured to the mouth-frame and 40 adapted to close said passage when the frame is folded.

A. F. MARTEL.
